EGG CARTON

Joseph A. O'Reilly, Bellingham, Wash.

Application December 6, 1949, Serial No. 131,345

6 Claims. (Cl. 229—29)

1

This invention relates to cartons of the multi-cellular types, such as those designed for the packaging of eggs and which are most generally made from a single strip of heavy paper, cardboard, or the like, that is cut, scored, folded and joined in such manner to form a carton that may be flatly collapsed for storage until its time of use, and may then be easily and quickly set up, either by mechanical means, or by hand, for the reception of eggs in the cells thereof.

It is the principal object of this invention to provide an improved carton of the above stated character; the improvements residing more particularly in the means for insuring greater safety to the contained eggs; for manufacturing expediency and for economy of material. The advantages of the present construction reside in providing the carton with a succession of spaced, transverse partition forming strips, and with intermediate cushioning strips at a lower level, on which latter the eggs are supported in the cells, spaced from the top and bottom walls of the carton. Also there being a longitudinal divider strip assembled with the partition and cushion strips, to divide the spaces, as set off between the partition forming strips, into two cells each; the divider strip being designed for interlocking both with the transverse partition forming strips and with the cushioning strips for the functional support of the latter, and for the positive holding of the carton against collapse while in use.

It is also an object of this invention to provide improvements, particularly in the manner of slitting, cutting and scoring the body blank for the defining and formation of partition walls and the cushioning strips and to make possible an easy manual or mechanical edgewise turning of the partition strips, and the downward offsetting therefrom of the cushioning strips upon erection or "setting up" of the carton for application of the divider strip thereto.

More specifically stated, the present invention resides in the manner of cutting, scoring and folding of a blank to form the carton body and the various transverse partitions and cushioning strips thereof, and to provide those details of construction that make possible the easy assembling of the divider therewith for the secure holding of the parts in their functional relationship and to insure the carton against collapse when set up.

In accomplishing the above stated and other objects of the invention, I have provided the improved details of construction, the preferred

2

forms of which are illustrated in the accompanying drawings, wherein—

Fig. 1 is a flat view of a "blank" as cut and scored for the formation of the present carton therefrom.

Fig. 2 is a view of the same, showing one end portion of the blank folded back upon the medial portion thereof as the first step in the making of the carton from the prepared blank.

10 Figs. 3 and 4, are edge views of the prepared blank, after the first and second folding operations, respectively.

Fig. 5 is an end view of the carton body, as formed by adjusting the folded blank from a 15 collapsed condition of Fig. 4 to "set up" condition, preparatory to receiving the divider strip therein.

Fig. 6 is a side view of the divider strip.

Fig. 7 is a vertical section on line 7—7, in Fig. 5.
20 Fig. 8 is a horizontal section, on the line 8—8 in Fig. 5.

Fig. 9 is a vertical section on line 9—9 in Fig. 5.

Fig. 10 is a perspective view of the carton as 25 erected and ready to receive the divider strip.

Fig. 11 is a similar view showing the divider strip as applied.

Fig. 12 is an elevation of a carton, with a part 30 of the front wall and locking flap broken away for better showing of the support of an egg in a cell.

Fig. 13 is a cross-sectional view of a carton that has eggs applied thereto.

Referring more in detail to the drawings—
35 In Fig. 11, I have shown a carton, designated in its entirety by numeral 1, which embodies the various novel features of the present invention therein. As shown, the carton comprises six cells, to hold six eggs, but it is to be understood that 40 it might be extended in length to provide twelve, as is usual, or any other number of cells.

In the particular structure shown, it is anticipated that the carton in its entirety except for the divider strip, be made from a single, continuous strip of material, such as heavy paper or cardboard. Such a strip of material, which I refer to as the "blank," has been designated in Fig. 1 by reference numeral 2, and it is shown therein to be scored and cut in a specific manner, so that it may then be glued and folded, for example as in Fig. 4, and flat stacked for storage until time of use. Then, the flat or collapsed carton may be "set up" to form the ready for use carton of Fig. 1. In this form the carton comprises opposite side walls 3 and 4, a flat bottom

5 and a cover forming portion 6 that is formed along its free edge with a locking flap 7.

Referring more particularly to the carton forming blank 2 as shown in Fig. 1: It is observed that the blank is rectangular in form and is transversely scored from edge to edge for bending by straight lines indicated at 10, 11, 12 and 13 and 14. The locking flap 7 is set off at the left hand end of the blank by the line of scoring 10. That portion of the blank that is to form the cover 6 of the carton is set off between the lines of scoring 10 and 11; that portion that is to form the side wall 3 is set off between the lines of scoring 11 and 12; that portion that is to form the bottom 5 is defined between the lines 12 and 13; that portion that is to form the side wall 4 is set off between the lines 13 and 14, and the remaining portion of the blank, that is spanned by the bracket 15 in Fig. 1, is utilized in the formation of the partition forming and the cushioning strips, and an end strip for glued securement to the wall 3 after the blank has been folded to position of Fig. 4, as presently explained.

In the making of a carton of the present kind for holding six eggs, it is necessary that it shall have four cross walls, to form three transverse compartments, as shown in Fig. 10, and that there shall be three cushioning strips. The application of the longitudinal division strip to the carton in the intended manner, as has been shown in Fig. 11, divides the three transverse compartments into six cells.

Referring now more particularly to the blank 2 as seen in Fig. 1, it is to be observed that the end portion thereof set off between the transverse line of scoring 14 and right hand end edge of the blank is formed with six parallel, equally spaced cuts or slits, 20; these being parallel also to the side edges of the blank. At their right hand ends, as seen in Fig. 1, or at the left hand ends in Fig. 2, the cuts 20 terminate in alignment near the end edge of the blank. At their opposite ends the cuts terminate approximately in the score line 14. However, it is to be noted in Fig. 1 that, starting with the cut 20 nearest the top edge of the blank, the left hand end portions of alternate cuts terminate in angularly inclined portions 20'. The strips of material that are thus set off between the longitudinal edges of the blank and the succession of cuts 20 define the transverse partition forming and the cushion forming strips. The three cushion forming strips are each designated by reference numeral 22. The four partition forming strips are each designated by numeral 23.

It is to be noted also in Fig. 1 that the right hand end limits of those strips of material 22 from which the egg supporting cushions are to be formed, are defined by lines of scoring 25. These lines are located in exact transverse alignment across the adjacent end of the blank. The opposite end limits of the cushioning strips 22 are defined by lines of scoring 26 directly across the strips. The lines of scoring 26 are spaced from the lines of scoring 25 a distance that is equal to the width of the bottom of the carton as defined by the distance between the lines of scoring 12 and 13.

The left hand end limits of the partition forming portions of strips 23, as seen in Fig. 1, terminate in the transverse line of scoring 14, while the other end limits of the partition forming portions are defined by lines of scoring 28 directed transversely across the strips. The lines of scoring 28 are spaced from the line 14 a distance that is equal to the width of the bottom wall 3, as de-

fined between the lines 12 and 13. Each partition forming strip 23 is formed at opposite end limits, as established by the scoring 28 and line 14, with a slot 30, directed perpendicularly thereinto from its top edge and extending half way to the bottom edge of the strip. Also, each partition forming strip 23 is formed at opposite ends with slits 31-31 that are directed inwardly and downwardly at about a 30° angle from the ends of the top edges of the partition forming strips, to the central longitudinal center line of the strip, and lines of scoring 35 extend from the inner ends of these slits 31 at opposite ends of the strips, outwardly to the lines 14 and 28. Also, cuts 36 and 36' are formed at the opposite ends of the partition forming strips, in coincidence with the lines of scoring 14 and 28 between the outer ends of the cuts 35 and the lower ends of the next lower cuts 20', reference being had to Fig. 1.

Shallow notches 40 are cut in the opposite edges of the cushion strips 22 midway of their opposite ends as defined between lines of scoring 25 and 26, and crossed cuts 42 are formed in these cushioning strips at locations halfway between their ends and the line of notches 40.

Preparatory to folding the blank, 2, after being prepared as seen in Fig. 1, those portions of the three strips 22, which are between the lines of scoring 14 and 26 may, if desired, have glue spotted thereon, as indicated at 45. Then that end portion of the blank, within the bracket 15 of Fig. 1, is folded back, along the transverse line 14, onto the medial part of the blank, as has been shown in Fig. 3, and the glue carrying parts of the strips will be flatly engaged against that underlying portion of the blank which later comprises the side wall portion 4. After the first folding operation, which has been shown in Figs. 2 and 3, the end portion of the back turned length of the blank, is then given a glue line 46 close along the edge of the strip as shown in Fig. 2, and extended if desired, into the strips 22 as at 46x. Finally, the left hand end portion of the blank is folded back, over the inwardly folded opposite end portion, as in Fig. 4, and the glued parts will be caused to be secured to the inner surface of the wall forming part 3.

Blanks that are cut and scored, as in Fig. 1, and then folded as in Figs. 3 and 4, may be flat stacked for storage until ready for use. Then, to prepare a carton for use, the collapsed structure may be set up as has been illustrated in Figs. 5 and 10. The erection or setting up of the body starts with the folded blank in position of Fig. 4. Then, while holding the left end fold against an abutment, pressure toward the left is applied against the right hand end portion, in the direction of the arrow in Fig. 4, and this pressure causes the side wall forming parts of the blank to hinge upwardly along the scored lines 12 and 13, which are at the locations 12x and 13x in Figs. 4 and 5, thus to cause the parts that constitute the side walls 3 and 4, bottom wall 5 and partition strips to form the rectangular body of Fig. 10. It is to be explained, however, that in this operation of setting up the carton, the strips 22 which are to form the cushion strips, are caused to be bent along the lines of scoring 26 and 25 while strips 23 are bent on lines 14 and 28. This will be accomplished automatically by reason of the fact that the end portions of strips 22 shown in Fig. 1 to be between lines of scoring 14 and lines 26, will be glued to wall 3, and the end of the blank and parts of strips 23 outside of lines 28 will be glued

to wall 4. Thus, while all strips 23 are brought to one horizontal level, the cushion strips will be brought into the same, but lower level as in Fig. 5.

After the carton has been erected to the condition of Figs. 5 and 10, the partition forming strips 23 are hinged from horizontal position of Fig. 10 to vertical position of Fig. 11 and are held in this latter position by the application of the longitudinal partition strip thereto.

The longitudinal partition strip 50 is shown in Fig. 6 to comprise a single strip of cardboard having a length equal to the length of the carton and a width that is substantially equal to the depth of the carton. The strip is formed along its lower edge with deep cut slots 51 leading directly upwardly thereto; these slots being slightly flared at their lower ends to facilitate the application of the strips. Between the slots, 51, which are spaced in accordance with spacing of the partition walls 22, are upwardly formed recesses 52, and these have notches 53—53 cut in their opposite side walls at the same horizontal level as best shown in Fig. 6.

After a carton has been brought from collapsed condition to the set up condition of Fig. 10, the partition strips 23 are each turned from horizontal position to vertical position by bending the material along the scored lines 35, causing the edges of the partition strips that contain the notches 30 to be swung upwardly and the unnotched edges to be swung downwardly. The division strip 50 is then applied lengthwise of the carton in such manner that the downwardly opening notches 50 of the strip and the upwardly opening notches 30 of the partition strips are interfitted, as seen in Figs. 11 and 12. When the division strip is thus applied, the lower edge of strip 50 will be close to the bottom wall of the carton, and the cushioning strips will be received within the recesses 52 and the edge notches 40 thereof will be seated in the notches 53—53 of the opposite edges of the recesses 52. The position of the cushion strips 22 when properly applied to the notches 52 has been indicated in dotted lines in Figs. 6 and 9.

It is to be explained further that the applying of the division strip 50 as illustrated, causes the partition strips 23 to be held in vertical positions as shown. Also, when the partition strips are so held, the depending, triangular corner portions thereof, designated by reference character *f* in Figs. 1, 3 and 13, and set off by the cuts 20' and 36 shown in the blank of Fig. 1, will engage along their vertical edges with the inside surface of wall 3 and will hold the carton against return toward the flattened condition of Fig. 4.

With the carton blank so formed, and the blank folded and secured as described, the collapsed carton may be easily, and quickly erected from condition of Fig. 4 to condition of Fig. 10. Then by turning the partition strips vertically and applying the division strip 50 thereto, the carton will be held against collapse. The cushion strips remain in horizontal position supported intermediate their ends by interengaging with the recessed lower edge portions of the strip 50 as in Fig. 9.

The two rows of cells of the carton, that are defined between the partition strips and at opposite sides of the division strip, receive the eggs as has been shown in Figs. 12 and 13. Eggs, so located, will rest at their lower ends on the slotted portions of the cushion strip, and will be held free of the bottom wall of the carton. The cross slitting, 42, of the cushion strips compensate for

eggs of different size, and gives additional cushioning effect.

The closing of the carton is accomplished by folding the cover portion 6 down over the top of the carton body. The locking strip 7 is formed with hooks 60 and these are arranged to be engaged with the triangular portions *k* which are attached to wall 4 and separated from the strips 23 by the diagonal cuts 31, and which remain in horizontal position when the partition strips are folded to vertical position.

Having thus described my invention, what I claim as new therein and desire to secure by Letters Patent, is:

1. A cellular carton comprising a blank that is scored and folded to form a back wall, a front wall, a bottom and a horizontal top panel; the panel being divided into a succession of transverse strips; alternate strips being vertically turned to form partitions that define a succession of cell spaces along the carton, and the other strips being offset downwardly from the plane of the panel to provide bottoms for the said cell spaces; said latter strips being supported spaced from the carton bottom.

2. A collapsible cellular carton of the character described comprising a blank that is scored and folded to form a back wall, a front wall, a bottom and a top panel; the latter being cut to define a succession of transverse strips; alternate strips being vertically turned from the panel to define a succession of cell spaces along the carton, and the other strips being offset downwardly from the plane of the panel to provide bottoms for the corresponding cell spaces; said latter strips being spaced from the carton bottom, a divider strip applied to the carton lengthwise thereof; said strip having slots therein opening to its lower edge, each receiving a partition strip therein, and having means at its lower edge to interlock with the corresponding cushioning strips for their support.

3. A collapsible cellular carton of the character described comprising a blank that is scored and folded to form a back wall, a front wall, a bottom and a top panel; the latter being cut to define a succession of transverse strips; alternate strips being vertically turned from the panel to define a succession of cell spaces along the carton, and the other strips being offset downwardly from the plane of the panel to provide bottoms for the corresponding cell spaces; said latter strips being supported free from the carton bottom, said partition strips each having a slot therein opening to its top edge; and a divider strip applied lengthwise of the carton, having slots opening to its lower edge, interengaged with the slots of the partition strips to retain the divider in upright position and the partitions in definite spacing, and having recesses in its lower edge supportingly containing the cushioning strips intermediate their ends.

4. A cellular carton comprising a blank of strip form that is scored and folded to form a back wall, a bottom, a front wall and a top panel that extends from the top edge of the front wall to the back wall and then downwardly therealong and is secured to the said back wall along its lower edge; said top panel being cut transversely between the front and back walls to define partition forming and cushioning strips in alternating relationship along the carton; said partition forming strips being cut at their ends and hinged and turned vertically to define cell spaces between them and the cushioning strips being

downwardly offset into a plane that is below the plane of the partition strip and above the bottom for the support of eggs thereon as retained in the cell spaces.

5. A cellular carton comprising a continuous, rectangular strip of cardboard or the like, that is scored transversely and folded at the lines of scoring to form a container comprising a cover portion, a back wall, a bottom, a front wall that is of substantially lesser height than the back wall, and a top panel that continues horizontally from the top edge of the front wall to the back wall, terminating in a downturned flange that extends to the bottom and which flange is secured along its lower edge to the back wall; said top panel being formed with spaced, parallel cuts that extend lengthwise of the blank, to define a succession of partition forming strips alternating with cushioning strips; said partition forming strips being so cut adjacent the back and front wall as to provide hinges on which they are turned vertically edgewise to fit at their ends between said walls and to define cell spaces between them; said cushioning strips being scored across their ends and folded at the lines of scoring, into a plane downwardly offset from the level of the partition strips, and in spaced relationship to the carton bottom to form bottoms for the

cell spaces, and a division strip applied to said cell spaces and formed with slits extended vertically thereinto from its lower edge, containing the top edge portions of the partition strips therein and there being recesses in the lower edge portion of the partition strip, supportingly containing the cushioning strips therein.

6. A structure as recited in claim 5 wherein the top edges of the partition strips are formed with vertical slits that are inter-engaged with the slits of the division strip, and said recesses of the division strip are notched at opposite sides to provide supporting shoulders seating the opposite edges of the cushioning strips therein.
